Primary Examiner — Daniel Bui*Assistant Examiner* — Andrew Kerr(57) **CLAIM**

The ornamental design for a water bottle with extended straw, as shown and described.

DESCRIPTION

FIG. 1 is a front view of a water bottle with extended straw showing my new design, a rear view being a mirror image thereof;

FIG. 2 is a left side view of the water bottle with extended straw;

FIG. 3 is a right side view of the water bottle with extended straw;

FIG. 4 is a top view of the water bottle with extended straw;

FIG. 5 is a bottom view of the water bottle with extended straw; and,

FIG. 6 is a perspective view of the water bottle with extended straw in use.

The broken line in the drawing views is included for the purpose of illustrating unclaimed environment only, and forms no part of the claimed design.
